UNITED STATES PATENT OFFICE.

AXEL O. TENGVALL, OF NEW YORK, N. Y.

ELECTRIC GOVERNOR FOR STEAM-ENGINES.

SPECIFICATION forming part of Letters Patent No. 339,826, dated April 13, 1886.

Application filed April 22, 1885. Renewed January 13, 1886. Serial No. 188,459. (No model.)

To all whom it may concern:

Be it known that I, AXEL O. TENGVALL, a subject of the King of Sweden and Norway, residing in the city of New York, in the county 5 of New York and State of New York, have invented certain new and useful Improvements in Electric Governors for Steam-Engines; and I do hereby declare that the following is a full, clear, and exact description thereof, which 10 will enable others skilled in the art to which it appertains to make and use the same, reference being had to the accompanying two sheets of drawings, which form a part of this specification, and in which—

15 Figure 1 is a sectional view of the stop-valve and throttle-valve of a steam-engine equipped with my electric governor or regulator. Fig. 2 is a sectional view of the electric switch mechanism, which is actuated by the hydro- 20 static pressure at the stern of the vessel. Fig. 3 is a sectional view of the electric switch mechanism, which is attached to one of the shafts (preferably the main shaft) of the engine. Fig. 4 is a view of the same at right 25 angles to the view shown in Fig. 3. Fig. 5 is a diagram illustrating the method of attaching the said switch mechanism to the shaft. Fig. 6 is a similar diagram looking sidewise at the shaft, and Fig. 7 is a view illustrating 30 a modification of the device shown in Fig. 1.

Similar letters of reference indicate corresponding parts in all the figures.

My invention has relation more particularly to electric governors for marine engines. In 35 this class of engines there are at present two distinct classes of governors—viz., those whose action is influenced by the variation of motion or speed of the engine itself, and those whose action is due to the motion of the sea only. The former class, if properly designed and 40 constructed, will check "racing" from any and every cause, but is necessarily slow in its action; nor does it always prevent the engine from acquiring a dangerous change of velocity, 45 and the latter, while it anticipates a change in velocity, and, if properly designed and constructed, prevents it, does not check racing from every cause—as, for instance, if the racing is caused by the breaking of the propellor 50 or propellor-shaft.

In marine engines, as is well known, the engine will run, or should run, at its normal speed

as long as the propeller is fully immersed, but the moment a part of the propeller gets out of the water the engine or engines will commence 55 to "race." When this happens, it becomes necessary to partially close the throttle-valve so as to regulate the steam supply to correspond to the hydrostatic pressure at the stern of the vessel, and, if possible, this should be 60 effected by the said hydrostatic pressure. In all governors hitherto designed and founded on this principle with which I am acquainted the area through the throttle-valve has been made to vary in direct proportion to the hydrostatic pressure at the stern of the ship; but, 65 inasmuch as the speed of the engine does not vary directly either with the area through the throttle-valve or with the head of water at the stern, it will readily be seen that such governors cannot effectively control the speed of 70 the engine, except under certain limited conditions.

The object of my invention is to overcome all these difficulties by constructing a governor 75 which will at all times prevent a dangerous change of velocity from whatever cause and absolutely control the speed of the engine under all conditions and circumstances. I attain this object by the mechanism which will be 80 hereinafter more fully described and claimed, reference being had to the accompanying two sheets of drawings, the figures of which have been already explained.

Commencing with Fig. 1, which, as we have 85 seen, represents a sectional view of the stop-valve and throttle-valve, A denotes the main stop-valve, which, in opening and closing, is guided by the cylindrical projection of the valve-seat B, which is provided with parallel 90 grated openings of ample area. The throttle-valve C is provided with corresponding openings, so that by pulling down or raising the latter, the area through the valve may be decreased or increased. The spindle 95 D of the throttle-valve passes through a stuffing-box, E, and is provided with a disk, F, at its projecting end, to which is attached one or more springs, G, in such a manner as to take up or compensate for the weight of the throttle-valve and its spindle, so as to keep the valve open under normal conditions. A series 100 of electro-magnets, two of which are shown at H' and H², are suitably fastened to

the valve-casing or to any other suitable frame or support, and are provided with armatures I' and I^2 , which armatures are connected to levers J' and J^2 , provided with sliding pieces K' and K^2 , which may be fixed in their adjusted position upon the levers by means of set-screws or binding-screws. It will be seen that when an electric current passes through the electro-magnets these will attract their respective armatures, and thereby depress the levers J' J^2 , with their sliding pieces K' K^2 . These sliding pieces K' and K^2 bear or press against levers L' and L^2 , the free ends of which bear upon and press against the top or face of the disk F at the projecting end of the valve-spindle D , and it will be seen that by moving the sliding pieces K' and K^2 forward or back upon their respective levers J' and J^2 the stroke or limit of motion of levers L' and L^2 may be regulated in such a manner as to regulate the stroke of the spindle D and throttle-valve C . In other words, it will be seen that the area through the throttle-valve C may be more or less throttled without increasing the distance between the electro-magnets and their respective armatures simply by changing the position of the sliding pieces K' and K^2 .

Having in the foregoing described the construction and arrangement of the stop-valve and throttle-valve and its adjuncts, I shall now proceed to describe the mechanism for governing the valve by the hydrostatic pressure which obtains at any given time at the stern of the ship. This device is illustrated in Fig. 2 of the drawings, on which M denotes a pipe which communicates with the sea by means of a suitable cock or valve. This pipe opens up into a cylinder, P , in which works a piston, N , the rod N' of which is provided at its upper end with contact-pieces b' and b^2 . A coiled spring, O , bears with one end against the piston N , and with its other end against a collar, e' , which may be adjusted by means of a nut, e , so that the tension or pressure of the spring O against the piston N may be increased or decreased by lowering or raising the screw or nut, e . This nut having been properly adjusted to exercise the required pressure against the piston, it will be seen that the latter will be affected on its opposite side, where it faces the pipe M , by the pressure due to the head of water at the stern of the ship, so that the piston will be worked up or down within its cylinder P , according to the varying hydrostatic pressure at the stern of the vessel. The contact-pieces b' and b^2 are fastened to the upper end of the piston-rod by means of an insulating-piece, f , with which they are connected by the springs d' and d^2 , so as to bear against insulated metal strips a' , a^2 , and a^3 , arranged in a series one below another on the inner side of the box or casing, in which the upper end of the piston-rod plays, and fastened properly in the said casing. On the opposite side of this casing is placed an insulated metal strip, c , against which the contact-piece b' bears, as clearly shown on the drawings. The springs

d' and d^2 are connected to each other and fastened upon the insulating-piece f by means of narrow metal strips or bands encircling the insulating-piece, so as to be in metallic contact with each other, but, as we have seen, insulated from the piston-rod by means of the insulating-piece f , to which they are fastened.

Before describing the operation of this device I shall describe the construction of the switch mechanism, which is actuated by the speed of the main shaft, or any one of the other shafts of the engine adapted to be used for the purpose, and which said device is illustrated in Figs. 3, 4, 5, and 6. This device is worked by means of the centrifugal force, and consists of an insulating-piece, Q , which is fastened upon the main engine-shaft, or to some shaft that runs in connection therewith, in such a way that the line marked g shall coincide with the center line of the shaft. The insulating-piece Q , which is fastened in this manner to and revolves with the shaft, is extended on one side to form a frame or box, U , inside of which slides a weight, T , which is suspended by a spring, W , from the upper part of said box or frame. Another insulating-piece, R , is fastened at the free end of a stationary spring, S , bearing with its inner end against the revolving piece Q . The stationary part R is provided with contact-pieces h' and h^2 and the revolving part Q , which faces and rubs with its face against the stationary part R , is provided with corresponding contact-pieces h^2 and h' . The weight T , which is guided between the sides of the frame or bracket U , in which it slides, has attached to its free end by an insulated piece and springs in the same manner as the contact-piece described in connection with Fig. 2, two contact-pieces, c^2 and c^3 , one of which, c^3 , bears against the metallic strips j and k on one side, while the other, c^2 , bears against a metallic strip, l , on the other side. The tension of the spring W should be so arranged or adjusted that the weight when the engine is running at its normal speed sends the electric current through the metal strip j , while, when the velocity of the engine-shaft increases, the weight T will be forced outward by the centrifugal force overcoming the tension of spring W in such a manner as to send the current through the metallic strip or contact-piece k , the contact-pieces h^2 , and the electro-magnet H^2 .

On Figs. 5 and 6, Sheet 2, of the drawings, I have shown the manner in which the revolving frame or bracket U may be fastened to the shaft so as to coincide with its center line. This may be done conveniently by attaching it to the face of the forward shaft-coupling in the engine-room, the lower end of the stationary spring S being suitably fastened in the floor of the engine-room. Where there is no coupling the mode of attachment is substantially the same, the revolving part being fastened in that case to the butt-end of the shaft.

The operation of the apparatus, as a whole,

is as follows: Let V, Sheet 1, represent the electric battery, storage-battery, or the electro-dynamo machine by which the electric current is generated. The lines running out from and back to the battery represent in the form of a diagram the conducting-wires, and the arrows indicate the direction of the electric current. When the throttle-valve is open to its full capacity and the propeller is fully immersed, the piston N will be at the upper end of its stroke, and the current is then sent through the metal strip *a* and back to the battery without passing through the coils of any of the electro-magnets; but when the stern of the vessel is lifted out of the water, exposing part of the propeller, and thus decreasing the hydrostatic pressure at the stern, the spring O will overcome the pressure of the head of water, and, moving down, will send the current through the contact-piece *a'*, the coils of the electro-magnet H', and back to the battery. As soon as the current passes through the coils of the electro-magnet H' its armature I' is attracted, and the area through the throttle-valve is so reduced as to keep the engines under control. On the propeller emerging still more or becoming still further exposed, the piston N will, by the further reduction of the hydrostatic pressure against it, move still farther down until its contact-piece *b'* is opposite to and in contact with the fixed contact-piece *a'*, when the current will flow through *b'*, the metallic springs *d'* and *d*, which, as we have seen, are in metallic contact with each other, the movable contact-piece *b'*, the fixed metallic strip or contact-piece *a'*, the coils of the electro-magnet H', and back to the battery, and when this occurs it will be seen that the armature I' will be attracted, and thus still further reduce the area of the throttle-valve by means of the intermediate mechanism consisting of the lever J', with its adjustable slide K', the lever L', the springs, and the valve with its spindle. It will thus be seen that by introducing a sufficient number of electro-magnets and properly adjusting their several sliding pieces K' K'', &c., the engine can always be kept under perfect control, no matter how much of the propeller may be out of the water. Again, as long as the engine is running at its normal speed the electric current will pass from the battery or generator V through the contact-pieces *i'* and *i''*, (see Figs. 3 and 4,) the metallic contact-strips *l*, and through the contact-piece *j* back to the battery. If the propeller or any of the shafts should break, or if, for any other reason, the engine should acquire a certain increase of speed, the weight T will be forced outwardly by the increased velocity of the shaft, thus sending the current through the contact-strip *l*, the sliding contact-pieces *c'* and *c''*, connecting the same with the contact-pieces *j* or *k*, as the case may be, the contact-piece *k*, the revolving contact-piece *h'*, the stationary contact-piece *h'*, the coils of the electro-magnet H', and back to the battery or

generator V, thereby throttling the area through valve C and keeping the engine under control, so as to prevent any dangerous racing. The number of switches in this device may of course be increased at will to correspond to any number of electro-magnets and to suit any requirement.

If my improved governor is used for stationary engines or land engines, I dispense of course with that portion of the apparatus which relates to the regulation of the throttle-valve by hydrostatic pressure.

In Fig. 7 of the drawings I have illustrated a modification of the device shown in Fig. 1, which consists, mainly, in extending the stem or spindle D of the throttle-valve C in an upward instead of a downward direction through the stuffing-box E. The projecting end of the stem D is here, as before, provided with a disk, F, between which and the frame is interposed a coiled spring, G', serving to balance the weight of the valve and stem.

H' H'' designate the electro-magnets, the armatures of which, I' I'', are mounted upon or attached to levers J' J'', having adjustable sliding pieces K' K'', which in turn bear against the free ends of levers L' L'', which rest upon a collar, C', upon the projecting end of the stem D. The operation of this modification will be readily understood when reference is had to the foregoing description, and does not require to be further enlarged upon.

It will be readily seen that many other modifications and changes in the arrangement, as well as in the mechanical construction of the operating parts of my invention, might be made without in the least altering the principle thereof or changing its spirit, and the above-described modification has been selected merely as an example. I would therefore have it distinctly understood that I do not limit myself to the precise construction and arrangement of parts herein described, but reserve to myself the right to all modifications which may be resorted to without departing from the spirit of my invention.

Having thus fully described my invention, I claim and desire to secure by Letters Patent of the United States—

1. An engine-governor consisting of a throttle-valve, or a valve adapted to control the quantity or pressure of the fluid or gas from which power is derived, which valve is operated automatically by a number of independent electro-magnets, whose armatures are attached to adjustable levers connected with the valve-rod, and to which currents of electricity are communicated through a series of switches which are worked automatically, substantially as set forth.

2. In a marine engine, a governor consisting of the following essential elements in combination, viz: a throttle-valve, or a valve adapted to control the quantity or pressure of the fluid or gas from which power is derived, provided with a number of independent electro-magnets adapted to be excited conseq-

tively by an electric current, and to actuate consecutively the valve-rod, so as to increase or decrease the area of the valve, an electric battery or generator, a series of switches connecting said generator with the electro-magnets of the valve and adapted to be worked automatically by the varying speed of the engine, and a second set or series of switches connecting the generator with the electro-magnets of the valve, and adapted to be worked automatically by the varying hydrostatic pressure at the stern of the vessel, substantially as set forth.

3. The combination, in a throttle-valve for engines, of the main stop-valve, the fixed valve-seat having parallel grated openings, the movable throttle-valve having corresponding openings, the valve-rod having a disk or plate at its projecting end, the springs adapted to take up or compensate for the weight of the valve and valve stem or spindle, and a series of independently-operating electro-magnets provided with armatures connected to the plate or disk at the projecting end of the valve stem or spindle, so as to actuate the valve consecutively, thereby increasing or decreasing the area of the valve as the said electro-magnets are consecutively excited by an electric current, substantially as set forth.
4. The combination, in a throttle-valve for engines, of the main stop-valve, the fixed valve-seat having parallel grate-openings, the movable throttle-valve having corresponding openings, the valve-rod having a disk or plate at its projecting end, the springs adapted to take up or compensate for the weight of the valve and valve stem or spindle, a series of independently-operating electro-magnets, each

having its appropriate armature fixed to one end of a vibrating lever, the sliding pieces attached adjustably upon the long arm of said lever, and the intermediate levers actuated by the said sliding pieces and bearing with their free ends against the disk or plate at the projecting end of the valve-spindle, substantially as set forth.

5. In an electric governor for marine engines, the automatically-operating switch apparatus for controlling the electro-magnets of the throttle-valve by the hydrostatic pressure at the stern of the vessel, consisting of a closed cylinder communicating with the sea by a pipe through the stern of the vessel, a piston and piston-rod sliding within said cylinder, a spring bearing against the piston with a tension or pressure adapted to be varied to conform to the normal pressure of the water entering the cylinder, a pair of contact-pieces in metallic contact with each other, fixed upon but insulated from the piston-rod, a series of fixed switches or contact-pieces adapted to come into consecutive contact with the sliding contacts on the piston-rod, and a circuit connecting the said fixed switches or contact-pieces with a series of corresponding electro-magnets adapted to operate the valve which controls the quantity or pressure of the medium from which power is derived, substantially as set forth.

In testimony that I claim the foregoing as my own I have hereunto affixed my signature in presence of two witnesses.

AXEL O. TENGVALL.
